UNITED STATES PATENT OFFICE.

CHARLES A. ROBERTS, OF BUTTE, MONTANA.

GASOLINE-TANK-CAP LOCK.

Application filed May 12, 1926. Serial No. 108,658.

This invention relates to closures, particularly to caps designed for use in connection with the gasoline tank of automobiles, motor-boats, aeroplanes or the like, and has 5 for its object the provision of a cap provided with novel locking means whereby removal of the cap by an unauthorized person will be prevented, the device consequently acting as a great means for discouraging or 10 preventing theft of automobiles inasmuch as after the gasoline supply has been exhausted it will be impossible to replenish the supply without unlocking or breaking off the cap and in the latter instance the attendant at 15 a service station or other place where the gasoline is purchased will be apprised of the fact that there is something wrong and that the car is probably stolen, so that he will notify the police and apprehend the 20 thief.

An important and more specific object is the provision of a device of this character which can be released only by means of a suitable key of peculiar design carried by 25 the owner or other proper authorized person.

Another object is to provide a device of this character so constructed and arranged that in order to apply the cap it is merely 30 necessary that it be telescoped upon the filling neck of a tank or other device, the locking means acting automatically to engage in operative position and prevent removal of the cap except by use of the proper key.

An additional object is to provide a device of this character which will be simple and inexpensive in manufacture, easy to apply and use, positive in action, efficient and durable in service, and a general improvement in the art.

With the above and other objects and advantages in view, the invention consists in the details of construction, and the arrangement and combination of elements to be hereinafter more fully described and claimed, and illustrated in the accompanying drawings, in which:—

Figure 1 is a plan view of the device partly broken away and in section to illustrate the action, this view being taken from the side of a tank looking toward the filling neck.

Figure 2 is a cross sectional view through the filling neck with the cap applied, and

Figure 3 is a detail sectional view showing the use of a key for effecting unlocking.

Referring more particularly to the drawings, the letter A designates a portion of a gasoline tank or the like having a filling neck B which, as is well known, is ordinarily either externally or internally threaded and provided with some sort of closure cap. In carrying out the present invention, the usual cap is discarded and replaced by a cap 10 which may be constructed of any suitable material and in any desired size, depending upon the diameter of the filling opening or neck to be closed. The cap 10 is intended to be telescopically engaged upon the filling neck B and for this reason it is unthreaded but is provided with a depending flange portion 11 so as to be telescopically engaged upon the filling neck in closely embracing relation thereto. The cap is also provided with an inner depending flange 12 which fits within the neck B as clearly indicated.

Formed at the center of the cap and depending therefrom is a guide sleeve portion 13 within which is rotatably mounted a stem 14 having limited rotary movement, the extent of movement being governed by a pin 15 or the like operating within a slot 16 in the sleeve. The stem 14 carries a transverse member 17 which has its end portion formed with slots 18 within which are engaged pins 19 carried by spaced parallel but oppositely extending latch members 20 adapted to be projected into engagement beneath the inner surface of the tank A at 25 the neck or filling opening B. A coil spring 21 is provided and suitably anchored at one end and having its other end connected with the transverse member 17 for the purpose of normally urging this member 17 into 30 such position that the latches 20 will be extended into operative position. At their undersides the latch members 20 are beveled or inclined at the ends, as shown at 22 so that when the latch members are in their 35 normal or extended position and the cap 10 is placed upon the filling neck simply by pressing it thereupon, the inclined surfaces of the latch members will cause them to be automatically retracted so that the device 40 may be placed in position. Obviously, when the cap is placed in position, and the latch members passed through the bottom of the filling neck, they will spring outwardly under the influence of the spring 21 and engage beneath the underside of the tank A.

The intention is that use must be made

of a suitable key for effecting retraction of the latch devices 20 so that the cap may be removed, and in Figure 3, I have disclosed a key 23 which is represented as having a certain shaped end 24 adapted to be engaged within a socket 25 in the upper end of the stem 14, this stem of course terminating within the recess provided in the guide or sleeve 13 and not extending to the top 10 of the cap.

From the foregoing description and a study of the drawings, it will be apparent that I have thus provided a very simply constructed and inexpensive cap locking means whereby it may be held upon a gasoline tank or the like and be prevented from removal except by an authorized person or except by breaking it. However, a broken cap would indicate that there is something 20 wrong and a service man or other person dispensing gasoline to a motorist having a broken cap on his tank would be supposed to notify the police of the fact. Clearly, the device will act as a prevention of theft and should therefore be of material benefit 25 to the motoring public. It is thought that the construction, operation and advantages will be readily apparent to one skilled in the art without further explanation.

20 While I have shown and described the preferred embodiment of the invention, it should be understood that I reserve the right to make such changes in the form, construction and arrangement of parts as will

not depart from the spirit of the invention 25 or the scope of the subjoined claim.

Having thus described the invention, I claim:—

A closure cap for a tank opening, the opening having an upstanding flange thereabout, 40 comprising a body member of circular form having a depending inner flange portion adapted to be telescopically engaged within the filling opening and having an outer depending flange portion concentric with and 45 spaced from the inner flange portion and adapted to telescopically engage about said first named flange, said inner flange having transverse guide openings therethrough, latch bolts slidably mounted through said 50 openings and having their outer ends normally projecting beyond the first named flange and beveled at their lower sides, a bearing member located at the center of the cap, a cylindrical member rotatably mounted 55 within said bearing member, an arm secured to said cylindrical member and having its ends formed with elongated slots, pins carried by said latch members and slidably received within said slots, a spring connected with said arm and normally holding the same in position with said latch bars 60 extended, key operated means for rotating said cylindrical member, and means for limiting the rotation of said cylindrical 65 member in both directions.

In testimony whereof I affix my signature.
CHARLES A. ROBERTS.
